UNITED STATES PATENT OFFICE.

FREDERICK W. WOOD, OF JASPER, NEW YORK, ASSIGNOR OF ONE-HALF TO ALBERT R. SMITH, OF RATHBONE, NEW YORK.

SAFETY-RAZOR.

1,193,655.

Specification of Letters Patent.

Patented Aug. 8, 1916.

Application filed July 15, 1914. Serial No. 851,164.

To all whom it may concern:

Be it known that I, FREDERICK W. Wood, citizen of the United States, residing at Jasper, in the county of Steuben and State 5 of New York, have invented certain new and useful Improvements in Safety-Razors, of which the following is a specification.

My invention relates to improvements in safety razors, and as its primary object 10 aims to provide a safety razor wherein the blade can remain connected with its holder in the frame both for shaving and while being sharpened upon a strop, whereby time, annoyance and injury are saved, as well as 15 the cost of extra appliances ordinarily required for stropping the blades.

The invention as a further object contemplates means so arranged relatively to the blade and its support as to permit oscillation of the same during a sharpening 20 operation.

The above and additional objects are accomplished by such means as are illustrated in their preferred embodiment in the accompanying drawings, described in the following specification and then more particularly pointed out in the claims which are appended hereto and form a part of this 25 application.

30 In describing my invention in detail reference will be had to the accompanying drawings wherein like characters denote like or corresponding parts throughout the several views, and in which:—

35 Figure 1 is a side elevation of the razor, the blade being shown in a position ready for use; Fig. 2 is a longitudinal sectional view on the line 2—2 of Fig. 1; Fig. 3 is a 40 sectional view, the blade being shown in a position ready to be stropped; and Fig. 4 is a fragmentary view.

Referring now to the drawings by numerals, 1 designates that portion of the frame within which the blade 2 is arranged. Said 45 blade 2 is secured in any suitable manner as indicated at 3 to a rotatable shaft like support 4, the extremities of which are journaled within the sides of the frame 1 as indicated in Fig. 3 of the drawings. Be-

tween the frame sides and adjacent the extremities of the support, enlargements 5 are formed, one of the said enlargements being provided with teeth 6 formed at a point diametrically opposite to that face of the support having the blade 2 attached 55 thereto.

A sliding guard plate 7 is arranged between the sides of the frame 1, the respective extremities of the said plate 7 being provided with extensions 8 fitting grooves 60 or slots 9 of the frame sides, the said slots serving as guide means for the plate when moved or adjusted in a manner to be herein-after fully described. An elongated roller 10, extending parallel with the support 4, 65 is journaled within bearings 11 carried by the guard plate 7. Upon one end of the said roller 10 a segment 12 is mounted, the teeth of which, in the raised position of the guard plate, mesh into the teeth 6 of one of the 70 enlargements 5, the teeth when meshing serving as a means whereby the blade and its support may be oscillated only to a certain degree. An arm 13 is rigid with the segment 12, said arm working within a slot 75 14 of the guard plate, the terminals of the slot acting as stop means whereby movement of the segment in a stropping operation is limited. Upon the opposite end of the roller 10 a cam head 15 is mounted, the said head 80 being disposed between extensions 16 of a substantially U-shaped spring 17, the connecting portion of which is rigid with the guard plate 7. By the provision of the eccentric 15 and the spring 17, it is apparent 85 that the roller 10 and the segment 12 carried thereby are at all times so positioned relatively to the teeth of one of the enlargements 5 as to move into mesh therewith when actuated. As illustrated to advantage 90 in Fig. 2, the guard plate 7 is semi-circular, one of the longitudinal edges being extended laterally as indicated at 18 to form a rest for the blade 2 when positioned for use. Retaining lugs or lips 19 are rigid or integral with the guard plate 7, said lips being 95 adapted for engagement with the cutting edge of the blade to serve as a means where-

by the blade is held in place, flat upon the guard, when in use.

A hollow handle 20 is made fast to that portion of the frame designated 1, said handle being hollow to receive the stem 21, rigid at one end with the guard plate 7, said stem being movable longitudinally with respect to the handle and held against circumferential movement therein through the medium of a pin 22 operating within a longitudinal slot 23 of the handle. An operating screw 24 of a length sufficient to fit a threaded recess therefor within the stem 21 is so related with the handle as to be turnable therein, but incapable of longitudinal movement independent thereof. A sleeve or band 25, rigid with the handle 20 at its free end, encircles the screw 24 and, as the said screw is constricted at this particular point, longitudinal movement thereof, when turned, is impossible. Any suitable form of head or knob 26 may be provided for the screw.

When it is desired that the blade 2 be used for shaving purposes, the guard plate 7 is moved, through operation of the screw 24, away from the blade support 4, whereupon the blade and its support are swung in the arc of a circle as indicated by the dotted lines in Fig. 2 into the position indicated in full lines therein, after which operation, the screw 24 is reversely turned to move that portion of the guard plate 18 into engagement with one of the lateral faces of the blade. A continued movement of the guard plate in a direction toward the support will position the cutting edge of the blade beneath the retaining lugs 19, in which event oscillatory movement of the blade cannot be effected, the blade being thus held rigidly ready for use.

When a stropping of the blade is to be effected, guard plate 7 is again moved, through operation of the screw, away from the blade, until the retaining lugs 19 are out of engagement therewith. Blade 2 is then swung into the position indicated in dotted lines in the said Fig. 2, whereupon the operating screw 24 is reversely turned until teeth of segment 12 mesh into teeth 6 of one of the enlargements 5. When in mesh, oscillation of the blade during a stropping operation is limited by the terminals of slot 14, the arm or extension 13 of the segment being engageable first with one of the slot terminals and then with the other. Spring 17, by reason of its engagement with cam or eccentric 15 at all times maintains segment 12 in proper position, and when the teeth of the segment are already in mesh with the teeth 6 of the enlargement, serves as a means whereby the blade 2 is held alined with the frame 1 and the handle.

It is to be understood that the strap, during a sharpening operation, may be ar-

ranged over the roller 10, between said roller 65 and the guard 7, the razor suspended from any suitable support and the strap drawn back and forth over the roller and the blade oscillated in the manner desired. A sharpening of the razor may also be effected by 70 simply drawing the blade back and forth over a straight line strap and in a manner common to the art.

From the foregoing, taken in connection with the accompanying drawings it will be 75 noted that the blade 2 may be positioned for stropping or for use without removing it from engagement with its support; that if desired, through manipulation of a suitable screw 27, the blade may be removed from 80 its support and a new blade substituted therefor; and that the only operation necessary to effect the various adjustments of the guard plate is the turning of the operating screw 24.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may 95 be resorted to, when required, without sacrificing any of the advantages of my invention as defined in the appended claims.

Having thus fully described my invention, what I claim as new and desire to secure by 100 Letters Patent, is:—

1. In a safety razor, a hollow handle, a frame secured to said handle, a rotatable support carried by said frame, a blade secured to said support, a combined guide and guard movable relatively to said frame, a rotatable means secured to said combined guide and guard and turnable within said hollow handle to move said combined guide and guard, a segment mounted on said support, a roller movable with said combined guide and guard, a segment mounted on said roller for engagement with said first mentioned segment to oscillate said blade in one position of the combined guide and guard, and a means on said combined guide and guard to engage with the blade to lock said blade against movement, substantially as described.

2. In a safety razor, a movable blade, a support therefor, teeth upon said support, a blade guard, an operating screw actuatable to move said guard, a segment carried by said guard, said segment being movable with said plate into and out of engagement with the teeth of said support, means integral with said segment and operating within a slot of said guard plate to limit

movement of the support and the blade carried thereby, means operable to aline the teeth of the segment with the teeth of said support, and means upon said guard engageable with the blade to lock the latter immovable with respect thereto, as for the purpose set forth.

In testimony whereof I affix my signature in presence of two witnesses.

FREDERICK W. WOOD.
